J. L. GOBEILLE.

ADJUSTABLE BLOWER FOR STOVES AND FIRE PLACES.

No. 350,194.

Patented Oct. 5, 1886.

UNITED STATES PATENT OFFICE.

JOSEPH LEON GOBEILLE, OF CLEVELAND, ASSIGNOR TO THE GIRARD STOVE WORKS, OF GIRARD, OHIO.

ADJUSTABLE BLOWER FOR STOVES AND FIRE-PLACES.

SPECIFICATION forming part of Letters Patent No. 350,194, dated October 5, 1886.

Application filed February 13, 1886. Serial No. 191,826. (No model.)

To all whom it may concern:

Be it known that I, JOSEPH LEON GOBEILLE, a citizen of the United States, and a resident of Cleveland, county of Cuyahoga, State of Ohio, have invented a new and useful Improvement in Adjustable Blowers for Stoves and Fire-Places, of which the following is a full, clear, and exact description, reference being had to the accompanying drawings, making part of this specification.

My invention relates to improvements in adjustable blowers for stoves and fire-places; and it consists in providing means, hereinafter described, by which the blower may be balanced and held at any desired point of adjustment; also, in providing means for uniting the counter-weights, that uniformity of movement may be secured.

My invention also relates to the detail and combination of parts, as set forth in the claims.

Similar letters of reference indicate corresponding parts in all the figures of the drawings hereunto attached.

Figure 1 is a view in perspective of a stove, showing my invention with the blower A raised up and a section of the end plate, B, removed. Fig. 2 is same view, disclosing the interior of the stove, and showing the fire-plate L, segment M, and counter-balance N and plate O. Fig. 3 is a view of an end section of the front plate, C, showing the slot A'. Fig. 4 is a view of an end section of the blower A, showing the rack a. Fig. 5 is same view as Fig. 4, showing the other end of blower 35 with rack a'. Fig. 6 is a view in perspective of the toothed segments M and M', the counter-balances N and N', and the connecting-bar P; Fig. 7, same as Fig. 3, showing the slot A² in front plate, C.

In the construction of the stove the fire-grate and fire-box are incased by the vertical plates C, B, and K, and the bottom plates, F and G, and top plates, D and E, the end lining-plates, O O', and top fire-plate, L.

The blower A is provided at each of its ends with a toothed rack, a and a', which extends above and below the bottom of the blower. Said racks, having teeth b, are placed in the slots A' and A² of the front plate, C, and in which 50 they may be vibrated. The end lining-plates, O O', are provided with outwardly-projecting

pins f f, about which may be oscillated the segments M and M', which are made in pairs, and one adapted to each end of the stove and provided with teeth e, which engage with the teeth b of the racks a a'. To the hubs g g' is attached, and is integral therewith, the counter-balance N, as shown in Figs. 2 and 5. Said counter-balances N and N' are connected by the bar P, for the purpose of securing a uniform movement of the segments M and M', by which the blower A may be raised and lowered as may be desired, the counter-balances N and N' and the connecting-bar P being of such weight as may be necessary to balance 65 and to detain the blower at any desired point within the range of its described movement.

The blower A is held in position by the vertical plate R, against which rests the face or flanges h of the blower A.

The end lining-plates, O O', are provided with projecting pins k k', which arrest the upward and forward movement of the counter-balances N and N' when the blower A has reached the limit of its downward movement. The end plates, O O', are also provided with a slot, m m', semicircular in form, through which the bar P may pass.

The fire-plate L rests against the back plate, K, at n, and extends forward and upward, and over and upward, and backward and downward, on the lines of curvature, or thereabout, as shown by the dotted lines, and the removed section of plate L, to letter p, (see Fig. 2,) the point of juncture with the back plate, K. The open ends of the above-described fire-plate are adapted to the slots m m' and to the end lining-plates, O O'.

The manner of joining any or all of the plates used in the construction of the stove may be of 90 any of the well-known and approved methods.

In forming the fire-plate L, as hereinbefore described, an open space, T, is provided between the upper section, r, and the lower section, s, through which the bar P may pass in 95 forming a connection between the counter-balances N and N', as shown in Figs. 2 and 5. The back plate, K, is provided with a series of perforations, t, between the junctions formed with the plate K by the edges of the fire-plate L at n and p, through which cold air may pass 100 into the heating-chamber formed by the fire-

plate L and the back plate, K, in which chamber the air will become heated and flow through the apertures in the end lining-plates, O O', into the flue U U', formed between and by the plates B and O, and out through the perforations *w* in the top plate, E. Cold air may also enter the flues U through the perforations *v* in the end plate, B, and out at the top, as before stated.

10 The shield H covers the grate and front of opening into the ash-box. The doors *x* *x* in the base may be of any of the well-known and approved forms, having sliding dampers *z*.

15 The blower A is provided at its lower edge with a projecting ledge, *c*, adapted to cover an upwardly-projecting rib, *e*. (See Fig. 1.)

20 The operation of the vertically-moving blower A is as follows: The flanges *h* of the blower rest against the face of the front plate, C. The racks *a* *a'* in the slots A' A² are held in position by the vertical corner-plates R R', the teeth *b* of the racks *a* *a'* engaging with the teeth *d* of the segments M M', which are supported on and may be oscillated about the 25 projecting pins *f* *f'*. The weight of the segments M M' and the bar P being equal to the weight of the blower A, the parts will balance over the pins *f* *f'*, or so nearly so that a very slight pressure on the blower will cause it to move in the desired up or down direction, and to remain at any point of elevation or depression between the limits of its boundary.

30 Having thus fully described the nature and object of my invention, what I claim as new, 35 and desire to secure by Letters Patent, is—

1. The combination, in a stove or fire-place, of a vertically-adjustable blower having toothed racks, counter-weighted toothed segments engaging said toothed racks, and a bar connecting the weighted ends of the segments, substantially as described, and for the purpose set forth. 40

2. The combination, in a stove or fire-place, of a vertically-adjustable blower, A, having toothed racks *a* *a'*, counter-weighted segments M M', end lining-plates, O O', having projecting pins *f* *f'*, on which the segments and counter-weights may be supported, and about which they may be oscillated, and the slots *m* for the passage of the connecting-bar, and the connecting-bar P, adapted to rigidly connect the counter-weight M to the weight M', substantially as described, and for the purpose set forth. 45 50

3. The combination, in a stove, of the front plate, C, having slots A' and A², a vertically-adjustable blower, A, provided with toothed racks *a* and *a'*, adapted to and projecting through the said slots A' and A², the toothed segments M and M', engaging the toothed racks and provided with counter-weights N and N', 55 a connecting-bar, P, and an open way connecting the flue U and U', through which the bar P may pass and be vibrated, substantially as described, and for the purpose set forth. 60

In testimony whereof I have hereunto set 65 my hand this 9th day of February, A. D. 1886.

JOSEPH LEON GOBEILLE.
